POWER MOLDBOARD TILT FOR GRADERS
AND THE LIKE

Clarence W. Sowell, North Hollywood, Calif.

Application April 11, 1938, Serial No. 201,381

2 Claims. (Cl. 37—159)

This invention relates to improvements in graders and has particular reference to a grader wherein the blade may be tipped through a mechanical means and present various angles between the grader and the ground, thereby enabling the grader to be self-sharpening under certain conditions.

A further object is to produce a device of this character which is economical to manufacture, and one which may be applied to almost any standard form of road machinery, such as graders, levelers, and the like.

A further object is to provide means whereby the operator may tip the blade from a remote point without stopping the progress of the scraper.

A further object is to produce a device of this character whereby the strain may be relieved from the scraper blade quickly so as to avoid damage to the said blade.

Other objects and advantages will be apparent during the course of the following description.

In the accompanying drawings forming a part of this specification and in which like numerals are employed to designate like parts throughout the same,

Fig. 1 is a top plan view of my device;

Fig. 2 is a side elevation of Fig. 1, showing the blade in normal scraping position;

Fig. 3 is a view similar to Fig. 2, showing the blade tipped into a rearward position and capable of passing over a hard obstruction without injury to the scraper blade;

Fig. 4 is a fragmentary side elevation of one of the retaining dogs looking from the inside;

Fig. 5 is a side elevation of a slightly modified form of retaining dog showing an oblong opening for mounting it on the shaft; and

Fig. 6 is a side elevation, showing a section of the frame in reverse relation to that shown in Figs. 2 and 3.

Ordinarily, scraper blades are secured to a supporting framework from beneath the underside of a supporting turntable mounted on a vehicle. These scraper blades may be tipped to various angles and set to operate at any predetermined angle. When it is desired to change the angle, it is necessary for the operator of the vehicle to stop; and due to the weight of these devices, it usually requires the services of several men using hammers and crowbars in order to move the blade, with the result that considerable time is lost in the changing of the angle, and also this operation causes the blade to be supported unevenly.

With my device it is possible to pass over an

obstruction by tipping the blade from a remote point and continue scraping with the blade in this position, if desired; or the blade may be returned to its normal scraping position at an angle to the surface. Thus, through the abrasive action on the surface, the blade is practically self-sharpening and will, therefore, present a keen cutting edge throughout the life of the blade.

In the accompanying drawings wherein for the purpose of illustration is shown a preferred embodiment of my invention, the numeral 5 designates a portion of a supporting turntable having down-turned ends 8 and 9, which are attached to the moldboard 6 through the medium of the 10 stabilizer plates 13 and 14 and to which moldboard the blade 7 is secured in any desired manner. The down-turned ends 8 and 9 have pivoted thereto, as at 11, an auxiliary supporting bracket 12, which is attached to the moldboard 15 20. Stabilizer plates 13 and 14 are in turn attached to the moldboard 6 adjacent the ends 8 and 9. In order to rock the moldboard 6 and its attached parts, I employ a hydraulic ram which is pivotally mounted upon the turntable 5 through the medium of a pivot bracket 18, the ram being 25 designated by the numeral 19. This ram has its piston rod 21 connected to a crank arm 22, which is pivoted as at 23 to a bearing block 24 mounted upon the down-turned end 8 and in turn pivoted 30 as at 26 to a link 27, pivoted as at 28 to a bracket mounted on the moldboard 6. The stabilizer plates 13 and 14 are provided with curved slots 16 co-operating with the rollers 17 on the turntable for 35 bracing the same.

In order to hold the parts in adjusted position, I provide teeth 29 on the stabilized plates which are engaged by dogs 31 and 32 secured to a cross rod 33 and rotated through the medium of a downwardly extending arm 34 and a cable 36 extending rearwardly to the driver's compartment 40 of the vehicle.

In order to simplify the drawings the pipes conducting the hydraulic pressure to the ram have been omitted from Figs. 2 and 3.

The result of this construction is that when the parts are in the position shown in Fig. 2, and good ground is encountered, the scraper will be positioned as shown in this figure; but should some hard ground be encountered—that is, ground where the hard rocks protrude above the surface being scraped, or where accumulation of weeds, sticks, and the like may clog the scraping operation—then it is possible to move the scraper to the position shown in Fig. 3. This is accomplished 50 55

by the operator pulling upon the rope 36, which in turn will rotate the cross rod 33 and lift the dogs 31 and 32. Then by applying fluid pressure to the ram, the same will be forced from the position shown in Fig. 2 to that of Fig. 3, which will cause the moldboard and its attached parts to be moved about the pivot 11 until it has taken the desired position, after which the operator releases the cord or the rope, and the dogs will drop 10 into the teeth on the stabilized plates, thus maintaining the blade in the new adjusted position.

It is to be understood that the form of my invention herewith shown and described is to be taken as a preferred example of the same and 15 that various changes relative to the material, size, shape and arrangement of parts may be resorted to without departing from the spirit of the invention or the scope of the subjoined claims.

Having thus described my invention, I claim:
20 1. In a device of the character described, a supporting turntable having down-turned ends, a moldboard pivoted to said ends, a scraping blade secured to said moldboard, stabilizer plates secured to said moldboard, hydraulic means operable from a remote point and link connected to

said moldboard for moving said moldboard about its pivotal points, and means for locking said stabilizer plates and their attached parts in adjusted position including gravity actuated dogs carried by the turntable and capable of engaging 5 indentations formed on said stabilizer plates.

2. In a device of the character described, a supporting turntable having downwardly turned ends, a moldboard, a scraper carried by the moldboard, stabilizer plates secured to the moldboard 10 and pivotally mounted on the downwardly turned ends of the turntable, a hydraulic cylinder mounted on the turntable, a piston rod operated by a piston in the cylinder, a crank arm pivotally connected to the turntable, and having one end 15 pivotally connected to the piston rod, a link having one end pivotally connected to the other end of the crank arm and its end pivotally connected to the moldboard, the upper end of the stabilizer plates having segmental portions provided with 20 notches, and gravity actuated dogs carried by the turntable and co-operating with said notches for holding the stabilizer plates in their adjusted position.

CLARENCE W. SOWELL. 25
